TAPE THREADER FOR TEMPORARILY SECURING
MAGNETIC RECORDING TAPE IN A REEL

Henry J. Modrey, Eagle Drive,
Stamford, Conn. 06903

Filed Dec. 13, 1966, Ser. No. 5,014

Term of patent 3½ years

(Cl. D26—14)

FIG. 1

FIG. 3

FIG. 1 is a perspective view of a tape threader for temporarily securing magnetic recording tape in a reel, showing my new design;

FIG. 2 is a top view of the tape threader; and

FIG. 3 is a bottom view of the tape threader.

I claim:

The ornamental design for a tape threader for temporarily securing magnetic recording tape in a reel, as shown.
